his Attorney.

UNITED STATES PATENT OFFICE

CHARLES T. RASCHICK, OF ST. PAUL, MINNESOTA

CHECK HOLDER AND CUTTER

Application filed March 30, 1921. Serial No. 457,088.

My invention relates to check holders and cutters and has for its object to provide a check holder adapted to hold one or more books of checks with their edges projecting 5 toward the person of the user so that the checks may be removed from the same by tearing the checks outwardly from the side of the holder.

Another object of the invention is to provide 10 a cutter adapted to be positioned on the top of the holder so as to cover the edges of the checks contained within the same.

Another object of the invention is to provide 15 a means for engaging a number of pads of checks between the leaves thereof for holding the same on the holder, said means being formed out of the metal of said holder.

A still further object is to form the holder 20 so that the check pads may be easily inserted into or removed from the same.

In carrying out my objects I provide a supporting plate on which is formed a loop member to be used in securing the holder to the person of the user. This supporting member 25 is provided with pairs of inwardly turned ears adapted to engage in between the leaves of the pads of checks and has an upwardly turned body member from which extends a flange, having corresponding ears adapted to 30 engage the pad of checks on the opposite sides thereof. Said last named flange is provided with a cutter.

The full objects and advantages of my invention will appear in connection with the 35 detailed description thereof and are particularly pointed out in the claims.

In the drawings, illustrating the application of my invention in one form:

Fig. 1 is a front elevational view of my 40 invention.

Fig. 2 is a plan view of my invention taken from the open side of the holder.

Fig. 3 is a sectional view of the device taken 45 on line 3—3 of Figure 1.

Fig. 4 is a rear elevational view of my invention.

In the drawings I have shown body member 10 the whole length of the device which is formed on its upper side with a flange 50 member 12, issuing at right angles therefrom

and of uniform width throughout but constructed slightly shorter in length than said body portion. On the bottom of body portion 10 the same is provided with a narrow flange 13 at the central portion thereof and two projecting supporting members 14 and 15 are connected with said flange 13 and positioned at the ends of the holder, as will be clearly seen in the figures. The entire holder is open at its ends so that one or more pads of checks 55 may be inserted between the flange member 12 on one side of the holder and supporting members 14 and 15 and flange 13 on the other side of the holder against the body member 10 thereof.

For holding firmly the pads of checks in place on the holder I provide a pair of inwardly turned ears 16 and 17 on the flange member 12 on the end thereof opposite supporting member 15. These ears are formed 60 by severing portions of the metal of this flange from the top thereof and pressing said metal inwardly as clearly indicated in Figure 3. On the opposite side of the device on supporting member 15 are formed similarly 65 positioned projecting registering ears 18 and 19, ear 19 being cut out of the metal and turned inwardly similar to ear 17 while the ear 18 is formed from an extended portion of supporting member 15 and merely bent over 70 at right angles thereto. All of the ears 16, 17, 18 and 19 are preferably formed with 75 their edges sharpened or reduced in thickness as indicated in dotted lines in Figure 2 at 20. It can clearly be understood that when the 80 device is detached from the person of the user and a pad of checks laid on the body member 10 and slid inwardly into the holder in engagement with the lowermost ears 17 and 19, the sharpened edges 20 will engage in 85 between the leaves of the pad and become firmly embedded therein as the portion of the pad adjacent the staple for securing the leaves thereof together approaches the ears. When 90 the pad of checks has been forced into the device a sufficient distance these ears serve to firmly hold the pad in place within the holder.

As will be noted in Figure 3 the ears 16 and 18 are positioned away from the top 95 of the pad of checks 21 so that the entire pad 100

of checks 23 may be inserted into the holder and held in place therein in a manner similar to that used in securing the pad 21 to said holder. In this case the pad 23 is placed upon 5 the upper surface 22 of pad 21 and is held in place by the ears 18 and 16, as clearly indicated in the figures. It can clearly be comprehended that pads of checks of varying thickness may be used in this holder and the 10 same equally as firmly secured therein as when pads of a fixed dimension are used. In adapting the use of the device to pads of varied thicknesses the number of leaves of the upper pad inserted between 18 and 16 and the upper 15 surface 22 of the lower pad 21 may be varied to meet the requirements so as to hold the pads properly positioned and secured within the holders. It can therefore be seen that variation in the thickness of the pads will not effect 20 the security of adjustment of the pads to the holder.

For adapting the check holder with the checks mounted thereon to the person of the user, I provide a looped extension 24 which 25 is adapted to be hooked on a hook or attached to a chain or other fastening member for use in securing the same to the person of the user. These devices being of common use are not shown in the drawings.

20 The member 24 is formed integral with and extends outwardly from the pad supporting member 15 in the plane thereof, as clearly shown in Figure 4. In use the supporting members 15 and 14 and the looped 25 member 24 lie against the surface of the person of the user so that the checks can normally hang downward with the edges thereof extending inwardly toward the user. In removing the checks the end of the holder adjacent supporting member 14 is grasped by 30 the hand and raised from the user's person. In this position each used check may be swung outwardly from the pad to which it is attached and torn therefrom with a movement 35 extending from the front to the rear of the device. This is rendered possible since the supporting member 15 is of such a size and shape that the downward end 25 thereof falls short of the line of perforation 26 of the respective check pads 23 and 21. It can clearly 40 be seen that when any of the checks are swung outward the same are free from supporting member 14 so no obstruction is encountered in the tearing of the same from the pad toward the supporting members 14 and 15.

The cutter of my invention comprises a longitudinal tongue 27 struck out of the body flange member 12 and formed with a sharp edged pointed end 28. This tongue is raised 45 from the body portion of the flange 12 and spaced therefrom. The end 28 of this tongue is adapted to engage a V shaped notch 29 formed in an outwardly inclined portion 30 of the flange member 12 formed at the extreme end thereof. When a check is inserted

between the portion 30 and the cutting end 28 of tongue 27 and said tongue pressed inwardly a portion of the edge of said check is severed by shearing action from the remainder of said check, thus forming a notch at the edge of the check. To stiffen the bent up portion 30 of the device I provide two web members 31 and 32 formed by depressing the metal of the flange member 12 at either side of tongue 27 at the angle of connection of member 30 and said flange 12. These webs stiffen the connection between the member 30 and the flange 12 thereby insuring the proper position of the cutter 28 relative to notch 29 at all times.

To permit the easy removal of the check pads or stubs from the holder I remove a portion of the body member 10 at 33 adjacent to loop member 24 thereof by means of which the thumb may be inserted under the check pad and the same withdrawn from the holder. To get access to the last checks on the pad adjacent to body member 10 for removal of said checks, I remove a portion of the other end of body member 10 at 34 so that said checks may be made accessible by the insertion of the forefinger to the side of the device. It is therefore clearly seen that the removal of the checks and check stubs from the holder is simple and effective and that all of the checks are individually accessible for removal from the pads.

The advantages of my invention are manifest. The checks are so positioned in the holder that a number of pads of checks may be placed within the same so that same will not protrude beyond the person of the user to an extent greater than the width of one pad of checks. At the same time the checks are so arranged that the same may be easily removed from the pads with a movement natural and convenient to the user of the checks, the cutter of the device being so arranged that a minimum amount of movement of the user is required in removing and notching the check. With this form of device check pads of varied thicknesses may be as equally and effectively attached to the holder as pads of the same thickness. When the user of the holder has a partly used check pad left over from a preceding day, which he does not wish to throw away and requires at least one new pad for immediate use, a new pad may be placed on the bottom of the holder and the partly used pad inserted on the top 115 of the same. This eliminates the necessity of carrying about in the pocket of the user's clothing the new check pad until the old one has been completely used up, thus saving time and greatly facilitating matters for the users 120 of the checks.

In accordance with the patent statutes I have described the principles of operation of my invention, together with the apparatus which I now consider to represent the best 125

embodiment thereof, but I desire to have it understood that the construction shown is only illustrative and that the invention can be carried out by other means and applied to uses other than those above set forth within the scope of the following claims:

I claim:

1. A check holder comprising a body member and supporting members for a pad of checks extending upwardly from said body member and a member for attaching the holder to the person of the user extending from the edge and integral with one of said supporting members and projecting from one end of the holder whereby the checks can normally hang downwardly with the side edges on one side thereof extending inwardly toward the user.

2. A check holder comprising a body member and supporting members for a pad of checks extending upwardly from said body member on one side thereof and a flange member extending upwardly from said body member on the other side thereof, means for attaching the check holder to the person of the user secured to one of said supporting members, and means on said flange and one of said supporting members for holding a pad of checks within the holder.

3. A check holder comprising a body member, a pair of flanges turned up from said body member in parallel relation to one another, said flanges and body member being open at one end and inwardly turned ears formed on said flanges in superimposed relation to each other adapted to engage between the leaves of a pad of checks and to hold the same in place as said checks are slid between said flanges and said ears.

4. A check holder comprising a body member, a pair of flanges turned upwardly from said body member in parallel relation to one another, and a pair of oppositely facing inwardly turned ears disposed in the same planes formed on each of said flanges, said ears being formed by severing the metal of said flange near its center and pressing the metal inwardly in two directions to form a pair of parallel ears, said ears being in superimposed relation to each other.

5. A check holder formed from a single piece of sheet material, including a body portion upon which the back of a pad of checks is adapted to rest, a longitudinally extending flange projecting upwardly from said body portion, along one side thereof, a stout flange extending upwardly from one end of the opposite side of the body portion and another flange at the opposite end from the last mentioned flange and on the same side thereof, having an attaching loop formed therein.

6. A check marking device, including a body portion adapted to form a support for the bottom of a pad of checks, flanges extending upwardly from either side of the longi-

tudinal edges of said body portion, one of said flanges having an opening formed between the ends thereof for accessibility to the edges of the checks, a shearing tongue formed integral with one of said flanges and adapted to engage an aperture formed in an upwardly inclined angular portion of said last mentioned flange.

In testimony whereof I affix my signature.

CHARLES T. RASCHICK.
